UNITED STATES PATENT OFFICE.

IKE W. CAMPBELL, OF MEXIA, TEXAS.

BEDSTEAD-BRACE.

SPECIFICATION forming part of Letters Patent No. 691,352, dated January 21, 1902.

Application filed June 29, 1901. Serial No. 66,586. (No model.)

To all whom it may concern:

Be it known that I, IKE W. CAMPBELL, a citizen of the United States, residing at Mexia, in the county of Limestone and State of Texas, 5 have invented a new and useful Bedstead-Brace, of which the following is a specification.

This invention is an improved construction of bedstead-brace, the object being to provide an exceedingly cheap, simple, and efficient 10 device which can be applied to any and all beds now in use for the purpose of preventing the side rails spreading and dropping the slats.

With these objects in view the invention 15 consists, essentially, in connecting brace-wires to the head and foot boards and side rails and connecting the intermediate portions of said brace-wires by means of a coupling-bar, said coupling-bars having a series 20 of notches whereby the wire can be taken up; and the invention consists also in providing a suitable tool to be used in connection with the coupling-bar for the purpose of adjusting one of the brace-wires to the said bar.

25 The invention consists also in certain details of construction and novelties of combination, all of which will be fully described hereinafter and pointed out in the claim.

In the drawings forming a part of this specification, Figure 1 is a perspective view showing the practical application of my invention. Fig. 2 is a sectional view illustrating the manner of connecting the brace-wire to the coupling-bar. Fig. 3 is a detail perspective view 35 of the tool employed to effect such adjustment, and Fig. 4 is a detail perspective view of the coupling-bar.

In carrying out my invention I employ two brace-wires A, which are connected to the 40 head and foot boards and also pass through screw-eyes A', screwed onto the side rails of the bedstead.

B indicates a coupling-bar arranged intermediate the ends of the brace-wires, said bar

having hooks B' formed at each end, and intermediate the hooked ends the upper face of the bar has a series of notches B², thereby providing a series of essentially ratchet-faced projections B³. One of the brace-wires is hooked into one of the hooks B', while the other 50 wire is hooked into the opposite hook B' or placed in one of the notches B² behind the projection B³, and in order to conveniently operate the said wire in connection with the coupling-bar I employ a tool C, comprising a handle 55 C' and a hook member C². The lower portion of the handle is bifurcated, as shown at C³, and a hook is pivoted upon a pin C⁴, and at the lower end of the bifurcated portion is a cross-pin C⁵. The hook C² is bifurcated, as 60 shown at C⁶, for the purpose of straddling a coupling-bar and engaging the wire upon the opposite sides thereof. The pin C⁵ is adapted to be brought into engagement with the notched coupling-bar, while the hook straddles 65 the coupling-bar and engages the brace-wire. By throwing the handle rearwardly, as indicated in dotted lines in Fig. 2, the brace-wire is drawn rearwardly and moved into engagement with one of the series of notches. In 70 this manner all of the slack is taken up, and the side rails of the bedstead are held rigid, thereby preventing the dropping of the slats.

Having thus fully described my invention, what I claim as new, and desire to secure by 75 Letters Patent of the United States, is—

A bedstead-brace comprising a pair of longitudinally-arranged brace-wires connected to the head and foot boards and side rails, and the transversely-arranged coupling-bar 80 having hooks at its opposite ends and a series of notches intermediate its ends, substantially as described.

IKE W. CAMPBELL.
